FUEL FEEDING APPARATUS

Hal M. Cunningham, Belvidere, Ill.

Application March 19, 1931, Serial No. 523,831

4 Claims. (Cl. 158—36.3)

This invention relates to fuel feeding apparatus and is particularly concerned with a system for feeding oil to a burner. The invention, furthermore, is especially adapted for application to fuel oil burning systems which are arranged for intermittent burning, for example, as in domestic oil heating systems.

In general, the object of the present invention is the provision of an oil feeding system which is not subject to certain disadvantages and difficulties heretofore encountered and which attains the maximum degree of safety while providing for dependable operation, especially where the ignition or burning is intermittent.

The nature of the present invention will appear more clearly from a consideration of the following discussion of various types of fuel feeding systems heretofore employed:

The various types of gravity and vacuum feed arrangements heretofore used, it is now well recognized, impose a considerable hazard to the premises in which they are installed. There are many reasons why such dangers or hazards arise, among which might be mentioned the fact that gravity and vacuum systems necessitate the use of float controlled valves and the like which, in case of inefficient operation or failure, are likely to cause abnormally large feed of oil to the burner or flow of oil into the air supply pipes and the like and even flooding of the apparatus itself as well as of the premises. With such gravity and vacuum systems, furthermore, leaks or breakage in the delivery or supply lines are also likely to result in flooding or abnormal flow of oil, especially where the installation is designed for intermittent ignition and operation.

There are other types of feeding systems employing pumps which have been employed heretofore for the delivery of oil to the burner but, in their present forms, these are disadvantageous for the reason that they either necessitate the use of a plurality of connections between the pump and the source of supply (one for return of excess) or they are subject to difficulties (often extinguishment of the burner flame) as a result of the presence of air slugs or pockets. In this connection, it should be noted that it is virtually impossible, as a practical matter, to completely eliminate the periodic discharge of air slugs from an oil pump, particularly where the operation of the pump is intermittent, as it must be in a domestic installation. Such air slugs or pockets are also frequently found in the supply pipes as the result of leaks or ineffective valve operation.

Various devices or schemes providing for vent-

ing or discharge of air from fuel feed lines have been proposed for use heretofore, but such devices or schemes are undesirable for the reason that they involve the use of still further parts and the like which are subject to breakage or inefficient operation. Furthermore, even if the operation of such devices were reliable, they are undesirable as they necessitate the external discharge of air and vapors frequently having obnoxious or distasteful odors. In addition, in such systems as are adapted to the burning of relatively combustible or even explosive hydrocarbons, the discharge or venting of vapors and air produces an additional fire hazard.

The present invention is specifically concerned with the provision of an oil feeding system, preferably employing a feed pump, in which various of the foregoing difficulties heretofore encountered are completely eliminated. For example, it is an object of the present invention to eliminate air slugs from a pump, gravity or vacuum system by the use of an extremely simple arrangement of devices and connections between the oil supply and the burner. It should be noted, however, that while various features of the present invention may be employed in any one of the three general types of feeding systems above referred to, I prefer to employ the apparatus of the present invention in association with a fuel feeding pump.

Still more specifically, the present invention makes use of a closed vessel into which the oil supply line discharges and from which a pair of connections are extended to the line delivering to the burner.

How the foregoing objects and advantages are obtained will be apparent from a consideration of the following description taken with the accompanying drawing, in which

Figure 1 is a diagrammatic view illustrating the parts and connections of the present invention in their relative and cooperative relation, portions of oil supply, air supply and oil delivery pipes being included; and

Figure 2 is a view similar to Figure 1 but illustrating a different condition of operation as will appear more fully hereinafter.

In both figures, the reference numeral 3 designates an oil supply line through which oil is delivered preferably by means of a pump (not shown), into a closed vessel 4. The burner oil-feed line is indicated at 5 while the air supply line communicating therewith is shown at 6. At this point it should be noted that I prefer to deliver only a portion of the burning or combustion air under pressure to the supply line 6.

Connections 7 and 8 communicate with the vessel 4 at vertically spaced points and these connections are provided with valves 9 and 10, respectively. These valves may be of any suitable character such as float or other automatically operated valves, or fixed-opening valves, but I prefer to employ a manually actuable valve in order to afford the greatest possible degree of control in the operation of the burner. From inspection of the drawing it will be seen that the connections 7 and 8 unite, as indicated for example at 11, and communicate with the oil-feed line through an additional valve 12. At this time, it is noted that the disposition of a valve 12 at this particular point is not a part of the present invention per se, but is described herein in association with the other parts in order to bring out the cooperative relation existing. This valve, furthermore, is preferably of the "relief" type, the same being arranged to open, during operation of the oil feeding pump, at a predetermined pressure in the vessel 4 and connections 7 and 8. When the apparatus is not in operation, this valve closes and, of course, prevents flow, by gravity, into the air supply line.

Before considering the operation of the apparatus it should be observed that I prefer to adjust the valves 9 and 10 in such manner as to provide for a flow of oil through the upper connection 7 equal to about one-quarter of the flow provided for by the adjustment of the lower valve 10.

With such an adjustment of the valves 9 and 10, and with oil pumped through the connection 3 at, for example, ten pounds pressure, and with atomizing air delivered through the connection 6 at about one and one-half pounds pressure, the operation of the system is as follows:

Referring first to Figure 2, under the above noted operating conditions, oil, the level of which is indicated at A (above the point of communication of the connection 7) will flow through both of the connections 7 and 8. The combined or aggregate flow through the valves 9 and 10 opens the valve 12 and passes therethrough into the oil-feed line to the burner nozzle. The air entering through connection 6, of course, also passes through the line 5 and serves to atomize the oil at the nozzle, it being noted that the total volume of air employed for atomizing the oil, in a typical installation, may equal only about one one-hundredth of the total air required for efficient combustion, the remainder of such air being supplied secondarily at the burner.

Assuming now that a slug or pocket of air is delivered from the feed pump through the connection 3 and into the vessel 4 (an event which frequently, if not usually, occurs at the time the pump is started), said slug or pocket results in a decrease or lowering of the oil level in the vessel 4, as illustrated for example at A1 in Figure 1. With the vessel 4 properly proportioned with respect to the size and character of the entire installation, the flow of oil through the lower connection 8 to the oil-feed line 5 is always assured.

Under these conditions, the air in vessel 4 passes through the connection 1 and combines with the atomizing air to be discharged with the oil fed through the connection 8 at the burner nozzle. It should be noted that under ordinary circumstances, the amount of air which is eliminated through connection 7 is only a few cubic inches per hour, so that its effect is negligible in the average installation which provides, by way of example, sixty cubic feet of air delivered through

the connection 6. On the other hand, during the elimination of the air from the vessel 4 (with the valve adjustments above referred to) approximately four-fifths of the total amount of oil which the valves 9 and 10 will pass, continues to flow through the lower connection 8. The only effect of the elimination of the air slugs, therefore, is a temporary, relatively brief and only slightly diminished delivery of oil to the burner nozzle.

When the air pocket in the vessel is completely eliminated, of course, oil again flows through both of the connections 7 and 8 and the flame burns the total oil delivered through both of the connections.

According to the foregoing, I have provided an oil delivery of feeding system which provides a maximum degree of safety and dependability in operation, particularly where the ignition or burning is intermittent, it being noted that the delivery of air slugs from the feed pump does not extinguish the flame, but merely slightly diminishes the intensity or size thereof. Thus I have eliminated a very serious difficulty which has been encountered heretofore, i. e., the extinguishment 25 of the burner flame by virtue of the presence of air pockets or slugs in the oil-feed line by the use of a very simple, dependable and effective apparatus. The simplicity of the apparatus of the present invention should be noted particularly, 30 attention being called to the fact that many systems heretofore employed necessitated the use of one or more auxiliary lines extending from the feed pump to the oil supply tank or other source of supply. It is obvious, of course, that excess 35 oil delivered from a supply pump may be bypassed directly around the pump in a system in which the apparatus of the present invention is adopted as the return of air slugs to the supply tank or some other point of venting is not necessary.

In conclusion, it should be noted that many of the difficulties and dangers, for example, fire hazard due to flame extinguishment by air slugs, are eliminated.

I claim:—

1. In a pressure liquid fuel feeding system for oil burners; a device intermediate the fuel supply and the burner operable to maintain a continuous fuel feed irrespective of the presence of air slugs in the oil delivered thereto, said device including means forming a substantially sealed chamber connected with the fuel supply, and conduit means, having restrictive means therein, continuously connecting the burner with the chamber at vertically spaced points; whereby, in the absence of air slugs delivered to the chamber, fuel is fed therefrom into the conduit means at said vertically spaced points and whereby, upon the admission of air slugs into said chamber, the fuel and air separate vertically and the air is delivered to the conduit means at an upper one of said points and oil continues to pass into the conduit means at a lower one of said points.

2. In a pressure liquid fuel feeding system for oil burners; a device intermediate the fuel supply and the burner operable to maintain a continuous fuel feed irrespective of the presence of air slugs in the oil delivered thereto, said device including means forming a substantially sealed chamber connected with the fuel supply, and a pair of conduits, having restrictive means therein, continuously connecting the burner with the chamber at vertically spaced points; whereby, in the absence of air slugs delivered to the chamber, fuel is fed

therefrom into both of said conduits and whereby, upon the admission of air slugs into the said chamber, the fuel and air separate vertically and the air is delivered to the upper conduit and oil continues to pass into the lower conduit.

3. In a pressure liquid fuel feeding system for oil burners; a device intermediate the fuel supply and the burner operable to maintain a continuous fuel feed irrespective of the presence of air slugs in the oil delivered thereto, said device including means forming a substantially sealed chamber connected with the fuel supply, and a pair of conduits, having restrictive means therein, continuously connecting the burner with the chamber at vertically spaced points, the restrictive means for the upper conduit providing a passage of smaller cross-sectional area than that provided by the restrictive means in the lower conduit; whereby, in the absence of air slugs delivered to the chamber, fuel is fed therefrom into both of said conduit forks and whereby, upon the admission of air slugs into said chamber, the fuel and air separate vertically and the air is delivered to the up-

per fork and oil continues to pass into the lower fork.

4. In a pressure liquid fuel feeding system for oil burners; a device intermediate the fuel supply and the burner operable to maintain a continuous fuel feed irrespective of the presence of air slugs in the oil delivered thereto, said device including means forming a substantially sealed chamber connected with the fuel supply, and a pair of conduits, having restrictive means therein, continuously connecting the burner with the chamber at vertically spaced points, the restrictive means for the upper conduit providing a passage of smaller cross-sectional area than that provided by the restrictive means in the lower conduit; whereby, in the absence of air slugs delivered to the chamber, fuel is fed therefrom into both of said conduits and whereby, upon the admission of air slugs in the said chamber, the fuel and air separate vertically and the air is delivered to the upper conduit and oil continues to pass into the lower conduit.

HAL M. CUNNINGHAM.
